CLAIM

The ornamental design for a charger as shown and described.

DESCRIPTION

FIG. 1 is a perspective view of a charger embodying the new design;

FIG. 2 is a front view thereof;

FIG. 3 is a rear view thereof;

FIG. 4 is a right side view, the left side being a mirror image thereof;

FIG. 5 is a top view thereof; and,

FIG. 6 is a bottom view thereof.

FIGS. 1 and 3-6 show portions of the design in broken lines. The portions shown in broken lines form no part of the claimed design.
